CIRCUIT INTERRUPTER

Leon R. Ludwig, Wilkinsburg, Benjamin P. Baker, Turtle Creek, and Andrew H. Bakken, Edgewood, Pa., assignors to Westinghouse Electric Corporation, East Pittsburgh, Pa., a corporation of Pennsylvania

Application February 18, 1942, Serial No. 431,394

11 Claims. (Cl. 200—148)

The invention relates to circuit interrupters and, more particularly, to circuit interrupters of the fluid blast fluid operated type for high voltage high power circuits.

In high voltage circuit breakers of the type referred to, it is necessary to provide an external disconnect switch electrically connected in series with the current interrupting contacts to provide the extra insulation needed to effectively isolate the two parts of the connected circuit since the interrupting contacts are not capable of withstanding high voltages in the open position after the fluid blast is cut off.

It is important that the disconnect contacts should open only after the current flow has been completely interrupted by the current interrupting contacts, and it is also desirable that the current interrupting contacts close before the disconnect contacts on a closing operation in order to eliminate the necessity of providing fluid blast for the interrupting contacts during a closing operation.

Reliable sequencing of the operation of the current interrupting contacts and the disconnect contacts, coupled with the increasing demand for higher speed opening and reclosing operations presents a difficult problem in the provision of a satisfactory circuit breaker.

An object of the invention is the provision of a high voltage high power circuit interrupter of the fluid blast type having a set of current interrupting contacts and a set of disconnect contacts connected in series, and an improved compressed gas operating system capable of effecting high speed opening and closing of the two sets of contacts in a predetermined sequence.

Another object of the invention is the provision of a high voltage high power circuit interrupter embodying an improved compressed gas operating system of simple construction for operating the current interrupting contacts and the disconnect contacts and correlating their motions to insure the proper sequence of operation.

Another object of the invention is the provision of a high voltage fluid blast type circuit interrupter comprising series connected current interrupting contacts and disconnecting contacts, and an improved compressed gas operating system for sequentially opening and closing both sets of contacts to always interrupt the circuit at the current interrupting contacts and close the circuit by the disconnect contacts.

Another object of the invention is the provision of a circuit interrupter having a set of current interrupting contacts and a set of disconnect con-

tacts connected in series each operated by a separate fluid motor, the two motors being fluid interlocked in a novel manner to provide the proper sequence of operation of the contacts, without the use of intermediate levers or other intermediate moving parts.

Another object of the invention is the provision of a fluid blast high voltage circuit interrupter having current interrupting contacts and disconnecting contacts, and an improved compressed air operating system for sequentially opening and sequentially closing the contacts and which is capable of effecting rapid reversal of switching operations.

Another object of the invention is the provision of a circuit interrupter embodying an improved compressed air operating mechanism capable of effecting high speed opening and closing of the interrupter and rapid reversal of switching operations.

Another object of the invention is the provision of a circuit interrupter embodying an improved compressed air operating means comprising an operating cylinder and double acting piston for opening and closing the interrupter, and means automatically operated by the flow of operating compressed air to one end of the cylinder for simultaneously establishing an exhaust connection to atmosphere for the opposite end of the cylinder so that the air in the cylinder ahead of the direction of movement of the piston will not retard the movement of the piston.

Another object of the invention is the provision of a circuit interrupter embodying an improved compressed air operating means comprising a cylinder and double acting piston for opening and closing the interrupter, and exhaust or dump valve means operated automatically in response to the flow of operating compressed air to either end of the cylinder for dumping the air from the opposite end of the cylinder.

Another object of the invention is the provision of a high voltage circuit interrupter having series connected current interrupting contacts and disconnecting contacts, and a compressed air operating system for opening and closing the two sets of contacts in a predetermined sequence comprising a separate cylinder and double acting piston for each set of contacts, and dump valve means common to the two cylinders automatically operated by the flow of operating compressed air to dump the air from the portions of both cylinders ahead of the direction of movement of the pistons.

Another object of the invention in accordance with a modification thereof is the provision of a

high voltage fluid blast circuit interrupter having current interrupting contacts and disconnect contacts pneumatically operated in sequence to interrupt the circuit by the interrupting contacts followed by opening of the disconnect contacts, and wherein the interrupting contacts are automatically reclosed by a spring after the disconnect contacts have opened and the operating air has been cut off.

Another object of the invention is the provision of an improved high voltage fluid blast circuit interrupter which is simple, reliable in operation and relatively inexpensive to manufacture.

The novel structural features that are considered characteristic of the invention are set forth in particular in the appended claims. The invention itself, however, both as to structure and operation together with additional objects and advantages thereof will be best understood from the following detailed description of several embodiments thereof when read in conjunction with the accompanying drawings, in which:

Figure 1 is a side elevational view showing a high voltage circuit interrupter embodying the features of the invention;

Fig. 2 is an enlarged view, partly in section, showing the contact operating mechanism of the circuit interrupter.

Fig. 3 is a view, partly in section, of the arcing contact operating cylinder showing the dump valves and a portion of the pneumatic interlocking means, the view being taken at right angles to Fig. 2.

Fig. 4 is an enlarged fragmentary view, partly in section, showing the control valve assembly of the circuit interrupter.

Fig. 5 is a view, partly in section, of the control valve assembly shown in Fig. 4, as viewed at a right angle to Fig. 4.

Fig. 6 is an enlarged detail view, partly in section, of the opening valve mechanism of the circuit interrupter.

Fig. 7 is a diagrammatic view of the circuit interrupter and control circuits for controlling the operation thereof, and

Fig. 8 is detail view, partly in section, showing a modification of the invention.

Referring to the drawings, the reference numeral 11 designates a framework which may be formed of structural steel or other suitable material. Rising from the left-hand side of the framework 11 are a plurality of hollow supporting insulators 13, 15 and 17, only the first two of which are shown in Fig. 1, and all three being indicated in Fig. 5. Supported upon the upper ends of the insulators 13, 15, and 17 is a casing 19 for housing operating mechanism more clearly shown in Fig. 2. The casing 19 supports a hollow insulator 21 which in turn supports a circuit interrupting element 23. A hollow insulator 25 similar to insulator 21 extends upwardly from the circuit interrupting element 23 and has a metallic terminal cap 27 secured to the upper end thereof.

A stationary contact member 29 extends downwardly from the terminal cap 27 through the hollow insulator 25, and the lower end of this contact member projects into the chamber of the circuit interrupting element 23. A movable contact member 31 cooperates with the stationary contact member 29 and extends downwardly through the interrupting element 23 and hollow insulator 21. The lower end of the moving contact member 31 extends into the casing 19 and is rigidly connected to a corresponding piston of

the operating means as shown in Fig. 2 and which will hereinafter be more fully described.

The contact members 29 and 31 form the arcing contacts which are openable to provide a current interrupting break in the circuit controlled by the circuit interrupter.

The circuit interrupter is also provided with a pair of disconnect contacts electrically connected in series with the contacts 29, 31, and arranged to be operated in a predetermined sequence with the arcing contacts. The disconnect contacts comprise a relatively stationary disconnect contact member 33 mounted within a terminal cap 35 of a hollow insulator 37, and a cooperating movable disconnect contact member 39 supported on the casing 19. The stationary disconnect contact member 33 comprises an arm of conducting material pivotally mounted intermediate its ends by a pivot pin 41 on a bracket 43 secured to a plate within the terminal cap 35. The contact member 33 carries a cup-shaped finger contact assembly 45 at one end adapted to receive the free end of the movable disconnect contact member 39 in the closed position thereof. The finger contact assembly 45 is disposed in an opening formed by a sleet hood 46 provided on the terminal cap 35. Movement of the contact arm 33 about its pivot 41 is limited to a very small amount by stops (not shown). The contact arm is biased in a counterclockwise direction about its pivot 41 by a spring 51 which is compressed when the movable disconnect contact member 39 is in closed position. The tail portion 49 of the contact arm is connected by a flexible shunt conductor (not shown) to the terminal cap 35. The stationary disconnect contact assembly briefly described above is fully disclosed and some features thereof claimed in the copending application of Raymond Leitzel et al., Serial No. 444,498, filed May 26, 1942, now Patent 2,356,069, issued August 15, 1944, which is assigned to the assignee of the present invention.

The hollow insulator 37 having the terminal cap 35 is mounted on the right-hand end of the framework 11 and this insulator serves as a housing for transformers and other suitable instruments for the control of the circuit interrupter.

The movable disconnect contact member 39 comprises a tubular hollow rod of conducting material and is mounted and guided in suitable bearings for straight line sliding movement in the direction of its longitudinal axis, the axis of movement being disposed at an angle to the axis of movement of the arcing contact member 31. The contact member 39 is movable to a closed position in engagement with the stationary disconnect contact 33, and to the open position shown in Fig. 1 in which it provides an isolating break in the circuit capable of withstanding high voltages.

The movable arcing contact member 31 is electrically connected to the movable disconnect contact member 39 through the agency of resilient connector contact means 53 (Fig. 2), which is slidably engaged by the contact member 31, and by means of electrically connected conducting strips 55 and 57 which connect the contact means 53 to a similar connector contact means 59 in sliding engagement with the movable disconnect contact member 39. External circuit connections to the circuit interrupter are made to a terminal 61 on the terminal cap 27 and to a terminal 63 on the terminal cap 35. Thus from the foregoing

description it is apparent that when the circuit interrupter is in closed circuit position, the current flow proceeds from the terminal 61, terminal cap 21, stationary arcing contact 29, movable arcing contact 31, connector contact means 53, conducting strips 55 and 57, connector contact means 59, movable disconnect contact member 39, stationary disconnect contact 33 and terminal cap 35 to the terminal 63.

If the movable arcing contact 31 is operated to the open circuit position while the circuit interrupter is carrying a load, an arc will be drawn by the movable arcing contact member. Extinction of the arc may be accomplished by any suitable type of arc extinguishing means but preferably by an arc extinguisher of the fluid blast type which, for example, may be of the form fully disclosed and claimed in the copending application of L. R. Ludwig and B. P. Baker, Serial No. 373,856, filed January 9, 1941, and assigned to the assignee of this application. Since the present application is not directed per se to the arc extinguishing structure, it is believed that the general designation of an arc extinguishing unit 65 which is supplied with a blast of arc extinguishing fluid, such as compressed air, will be sufficient for the purpose at hand.

The movable arcing contact member 31 and the movable disconnect contact member 39 are operated in a predetermined sequence, to open and to closed position by a compressed air operating means which will be fully described hereinafter.

Fluid under pressure for extinguishing the arc drawn by the arcing contact member 31, and also for operating the contact members 31 and 39, is stored in a tank 67 mounted within the framework 11. Fluid, in this instance compressed air, is stored and maintained above a predetermined pressure in the tank 67 by a suitable motor driven compressor unit (not shown). Extending from the left-hand end of the tank 67 is an air conducting pipe or manifold 69 which has mounted thereon and in communication therewith, a blast valve mechanism indicated generally at 71. The blast valve mechanism comprises a valve housing 73 which communicates with a short section of hollow pipe 75 and through the same with the passage through the hollow support insulator 13. The passage through the insulator 13 communicates by way of a pipe 77 with the passage through the hollow insulator 21 which supports the circuit interrupting element 23. Thus fluid under pressure from the tank 67 is conducted to the arc extinguishing structure 65 in the chamber of the circuit interrupting element 23 by way of the manifold 69, blast valve 71, pipe 75, hollow insulator 13, pipe 77 and hollow insulator 21.

The blast valve mechanism 71 is more clearly shown in Fig. 4. The blast valve housing 73 has a valve 79 therein which is operated to open and closed position by a rocker arm 81 carried by a shaft 83 journaled in the side of the valve housing 73. The rocker arm 81 is actuated by a piston 85 operated within a cylinder 87. A spring 89 disposed within the cylinder 87 normally biases the piston 85 downwardly and holds the valve closed.

The flow of compressed air to the lower end of the cylinder 87 for causing opening of the blast valve is controlled by a pilot valve 91 which is normally biased closed and operated to open position by an electromagnet or solenoid 93. When the solenoid is energized, the pilot

valve is opened and compressed air from the pipe 69 is admitted through a passage 95, pilot valve 91 and a passage 97 to the lower side of the valve operating piston 85. This causes the piston 85 to be raised against the action of the spring 89 to rock the shaft 83 counterclockwise so as to open the blast valve 79 thereby permitting a blast of compressed air to flow through the insulators 13 and 21 to the arc extinguisher 65. When the solenoid 93 is deenergized the pilot valve closes, thereby causing the spring 89 to return the piston 85, and consequently the valve 79 to closed position shutting off the air blast.

The compressed air operating means for the contact members 31 and 39 comprises an operating cylinder 99 having a double acting piston 101 therein connected to the lower end of the movable arcing contact member 31, and a second operating cylinder 103 having a double acting piston 105 therein connected to the inner end of the movable disconnect contact member 39. The cylinders 99 and 103 are mounted in the housing 19, the cylinder 99 being secured at its lower end by bolts 107 to a casting 109 which is in turn bolted to the bottom 111 of the casing 19 and which forms the lower end closure of the cylinder. The lower portion of the contact rod 31 slidably extends, in a substantially fluid tight manner, through the offset portion of the blast air pipe 71 and through an opening in the upper head of the cylinder 99, the lower end of the contact rod 31 being connected to the piston 101.

The body of the cylinder 99 has a laterally projecting portion 113 (Fig. 3) adjacent the upper end thereof and formed integral therewith. The portion 113 is provided with a passage 115 communicating with the interior of the upper end of the cylinder, and with a port in communication with the passage 115. A compressed air line or conduit 117 is connected to the inlet port of the projection 113 and this compressed air conduit communicates at its other end with the passage through the hollow insulator 17 and through a compressed air line or conduit 119 (Fig. 5) to an opening valve means which controls the flow of compressed air for effecting an opening operation of the circuit interrupter. A similar projection 121 is formed integral with the body of the cylinder 99 adjacent the lower end thereof on the opposite side of the cylinder from the projection 113. The projection 121 has an inlet passage 123 communicating with the interior of the lower end of the cylinder 99 and has an inlet port communicating with this passage. A compressed air line or conduit 125 (Fig. 2) is connected at one end to the inlet port of the projection 121 and the other end of the compressed air line 125 is in communication through the passage of the hollow insulator 15 and through the compressed air line 127 with a closing valve which controls the flow of compressed air for effecting a closing operation of the circuit interrupter.

The operating cylinder 103 for the movable disconnect contact member is mounted in the casing 19 and the upper portion of this cylinder extends outside of the casing 19 through an opening provided therefore in an annular casting or support member 129 which is secured to a wall of the casing by a plurality of bolts 131. The annular casting 129 forms a support for the cylinder 103. The lower end of the operating cylinder 103 extends into a cylinder head 133 which closes the lower end of the cylinder, the cylinder head 133 being secured on the lower end of the

cylinder by means of a plurality of elongated bolts 135 (only one being shown) which extend through a flange formed on the cylinder head and which thread into the annular support member 129. The upper end of the operating cylinder 103 extends into a cylinder head 137 which is securely clamped on the upper end of the cylinder by a plurality of elongated bolts 139 (only one being shown) passing through a flange of the cylinder head 137 and threaded into the annular support member 129. A metal cover 141 is mounted on the cylinder head 137 and secured thereto by extensions of the bolts 139 which extend through a flange of the cover 141 and through the flange of the cylinder head 137. A closure cap 145 is tightly clamped over the upper end of the cylinder head 137 between the cylinder head and the cover 141 by means of the bolts 139. The tubular disconnect contact member 39 slidably extends into the cylinder 103 through bearing openings provided in the cover 141 and in the cylinder head 137. The cover 141 encloses the connector contact means 59 which resiliently and slidably engages the contact member 39. This contact means is electrically connected to the cap 145 and cylinder head 137 and the conducting strip 57, and the conducting strip 57 is electrically connected to the conducting strip 55 through the agency of a bolt (not shown), which clamps the ends of the strips 55 and 57 to the support member 129.

The lower cylinder head 133 is provided with passages 149 and 151 through which the compressed air for operating the disconnect contact 39 to closed position flows into the lower end of the cylinder beneath the piston 105. The upper cylinder head 137 is also provided with passages 153 and 155 through which compressed air is admitted to the upper end of the cylinder above the piston 105 to operate the disconnect contact member 39 to open position. A sleet hood 157 encloses the exposed portion of the cylinder assembly 103 and this sleet hood is secured by bolts (not shown) to the wall of the casing adjacent the support member 129.

Compressed air from the tank 67 is utilized to actuate the contact operating pistons 101 and 105. For this purpose, the manifold or pipe 69 is provided with two branches 159 and 161 (Fig. 5). The branch 159 leads to the opening valve mechanism generally indicated at 163 whereas the branch 161 leads to the closing valve mechanism generally indicated at 165.

The compressed air from the opening valve mechanism 163 is conducting through the pipe 119 to the passage through the supporting insulator 17 and through the compressed air line 117 to the upper end of the operating cylinder 99 to effect opening of the circuit interrupter. Compressed air for effecting closing operation of the circuit interrupter flows through the closing valve mechanism 165, pipe 127 and the passage through the hollow insulator 15 and compressed air line 125 into the lower end of the operating cylinder 99.

It is important that the disconnect contacts 33 and 39 should be open only after the arcing contacts 29, 31 have opened and the current flow has been completely interrupted by the last-mentioned contacts; otherwise a long uncontrolled arc may be drawn by the movable disconnect contact member 39. It is also desirable that the disconnect contacts should close after the arcing contacts have closed during a closing operation of the circuit interrupter so as to eliminate the

necessity of providing a blast of arc extinguishing fluid for the arcing contacts during closing of the interrupter. In accordance with the present invention, the proper sequence of operation of the arcing contacts in the disconnect contacts is accomplished by pneumatically interlocking the operating pistons for the two sets of contacts. For this purpose, the operating cylinder 99 of the disconnect contact member of the arcing contact 39 is provided with a projection 169 (Fig. 3) formed integral with the cylinder adjacent the upper end thereof directly opposite the projection 113. The projection 169 has an air passage 171 formed therein which communicates at one end with the interior of the cylinder at a point which is a predetermined distance below the upper end of the cylinder. The other end of the passage 171 communicates with a port provided in the projection 169 and this port is connected by a compressed air line or conduit 173 and a compressed air line or conduit 175 to the passages in the cylinder head 137 leading to the upper end of the disconnect contact operating cylinder 103. The compressed air lines 173 and 175 communicate with one another through an air passage 177 formed in the annular support member 129. The point of entry of the passage 177 into the cylinder 99 is so located that it is uncovered by the operating piston 101 after the piston has moved downwardly a predetermined distance in an opening direction, the distance being such that the movable arcing contact member 31 will have reached its full open position before the flow of compressed air through the compressed air lines 173 and 175 starts to move the disconnect contact member 39 out of engagement with the stationary disconnect contact 33. This arrangement allows the movable arcing contact member 31 to overcome static friction and come up almost to full speed and slide out of engagement with its stationary contact 29 before compressed air is admitted to the upper end of the disconnect contact operating cylinder 103. This insures that interruption of the current flow will also be completed before the disconnect contacts separate.

The lower ends of the operating cylinders 99 and 103 are also pneumatically interlocked to secure the proper sequence of operation of the arcing contacts and the disconnect contacts during a closing operation of the circuit interrupter. For this purpose the operating cylinder 99 is provided with a projection 179 (Fig. 3) formed integral with the cylinder adjacent the lower end thereof, and this projection has a passage 181 therein which communicates at one end with the interior of the cylinder at a point a predetermined distance above the lower end of the cylinder. The other end of the passage 181 communicates with a port formed in the projection 179 and this port is connected by a compressed air line or conduit 183 (Fig. 2) to the passage leading to the lower end of the disconnect contact operating cylinder 103. The point of entry of the passage 181 into the cylinder is located so that it is uncovered by the operating piston 101 after the piston is moved upwardly a predetermined distance in a closing direction, the location being such that the arcing contacts 29 and 31 will be completely closed before the compressed air closes the disconnecting contact member 39.

The pneumatic interlocking arrangement described above is much simpler and more reliable than mechanical or electrical interlocking arrangements for sequence operations.

In order to obtain a prompt and fast opening

operation following immediately after a closing operation of the interrupter, and to obtain a quick and fast closing operation immediately after an opening operation of the interrupter, it is necessary that the air in front of the direction of the movement of both pistons be quickly exhausted to atmosphere so as not to retard the switching motion of the pistons. In accordance with the present invention, this is accomplished by the provision of two dump valves one of which opens the lower end of each of the cylinders 99 and 103 to atmosphere and is operated by the flow of compressed air to the upper end of the cylinder 99, and the other of which opens the upper end of the two cylinders 99 and 103 to atmosphere immediately upon the flow of compressed air to the lower end of the operating cylinder 99.

Referring to Fig. 3, a dump valve 187 is mounted within the cylinder projection 179 in the air passage 181. The dump valve 187 is connected by a rod 189 to a piston 191 slidably mounted in a cylinder 193 formed in the projection 113 which contains the inlet passage 115 for the opening air. The top of the piston 191 is in communication with the passage 115 so that it is moved downwardly immediately upon the flow of compressed air into the upper end of the operating cylinder 99. This downward movement of the piston 191 by the opening air affects opening of the dump valve 187 thereby establishing communication between the passage 181 adjacent the lower end of the cylinder 99 and atmosphere through an atmosphere exhaust port 195. Since the passage 181 is in communication with the lower end of the operating cylinder 99 and also the lower end of the operating cylinder 103, opening of the dump valve 187 opens the lower end of both cylinders to atmosphere through the exhaust port 195.

A similar dump valve 197 is mounted in the passage 171 of the projection 169 adjacent the upper end of the operating cylinder 99. The dump valve 197 is connected by a rod 199 to a piston 201 which is slidably in a cylinder 203 formed in the projection 121 of the operating cylinder containing the passage 123 for admitting closing air to the lower end of the operating cylinder 99. When compressed air is admitted to the lower end of the operating cylinder 99 through the passage 123 to effect a closing operation of the interrupter, the piston 201 is immediately moved upwardly by the flow of compressed air and thereby effects opening of the dump valve 197 at the opening end of the operating cylinder 99. When the dump valve 197 is moved to open position it establishes communication between the passage 171 and outside atmosphere through an exhaust port 205. Since the passage 171 is in communication with the upper ends of both operating cylinders 99 and 103, the opening of the dump valve 197 opens the upper ends of both cylinders to atmosphere through the exhaust port 205. The dump valves 187 and 197 are normally biased to closed position by compression springs 207. The compression spring 207 of the valve 187 encircles a portion of the rod 189 and is disposed between a collar on the rod and the projection 179. Similarly, the compression spring 207 for the valve 197 encircles a portion of the rod 199 and is disposed between a collar on the rod and the projection 169.

The provision of the dump valves 187 and 197 and the operation thereof described above ensures low pressure ahead of the direction of move-

ment of both pistons 101 and 105 and consequently high speed operation of the contact members regardless of when the interrupter has received an operating impulse thus providing for high speed opening and also for high speed reclosing of the contacts of the circuit interrupter.

Referring to Fig. 6, the opening valve mechanism 163 comprises a valve housing 209 having a valve 213 adjacent the lower end thereof. The valve 213 has a stem 215 encircled by a spring 217 for normally holding the valve closed. The valve stem 215 is actuated to open position by a piston 219 operative within the housing 209, and the piston has an upper effective pressure reactive area greater than the lower area of the piston so that when the upper side of the piston is subjected to compressed air from the pipe 159, the piston will be moved into engagement with the stem 215 to actuate the valve 213 to open position. Compressed air is admitted from the pipe 159 to the upper side of the piston 219 through passages 221 and 223. Control of the flow of compressed air through these passages is obtained by an electromagnetically operated pilot valve 225 which is biased closed and adapted to be opened by a solenoid 221. Upon opening of the main valve 213, compressed air is permitted to flow from the pipe 159 through a main port 229 into the pipe 119. The flow of compressed air then proceeds through the pipe 119, hollow insulator 17, and pipe 117 to the upper side of the arcing contact operating piston 101 in the operating cylinder 99 so as to actuate the piston 101 to downwardly open circuit position and cause operation of the arcing contact 31 to open position and to also open the disconnect contacts 33, 39 after the opening of the arcing contacts. When the pilot valve 225 is closed, upon deenergization of the solenoid 221, pressure is relieved on top of the piston 219 and the piston is moved to its upper or normal position by a spring 231. The piston 219 has a sleeve 233 secured to the lower side thereof which serves to control a small bleeder passage 235 disposed in the housing 209. When the piston 219 is in its uppermost position, the sleeve 233 uncovers the bleeder passage 235, thereby connecting the upper side of the operating piston 101 to atmosphere. However, during the initial stages of movement of the piston 219 towards the valve stem 215, the bleeder passage 235 is closed by the sleeve 233.

The closing valve mechanism 165 is generally similar to the opening valve mechanism 163 and is more fully illustrated in Fig. 5. Referring to Fig. 5, this mechanism includes the valve housing 239 having a valve 241 operative adjacent the lower end thereof. The valve 241 has a stem 243 that is spring actuated to closed position. The valve stem 243, however, in this instance has an extension 245, the purpose of which will appear more fully hereinafter. Actuation of the valve 241 to open position is accomplished by the piston 247 operative within the valve housing 239 and slidably about the extension 245.

Control of the flow of compressed air from the pipe 161 to the top of the piston 247 is obtained by an electromagnetically controlled pilot valve 249 which is biased closed, and which is operated to open position by a solenoid 251. When the solenoid 251 is energized, the pilot valve 249 opens to permit a flow of compressed air from the pipe 161 to the upper side of the piston 247 which actuates the piston downwardly against the stem 243 so as to open the main valve 241. Compressed air will then flow from the pipe 161 through a

port similar to port 229 of the opening valve. Compressed air then flows through the pipe 121, hollow insulator 15 and pipe 125 to the lower side of the arcing contact operating piston 101 so as to actuate the movable arcing contact member 31 to the closed circuit position and to also close the disconnect contacts 33—39 after the closing of the arcing contacts. The piston 247 of the closing valve also controls a small bleeder passage 253 for the purpose of connecting the lower side of the operating piston 101 to atmosphere at the end of a closing operation.

In order to prevent improper operation of the operating mechanism which may be caused by conflicting control impulses being impressed upon the valve controlling solenoids 227 and 251, an interlock is provided between the opening and closing valve mechanisms 163 and 165. For this purpose, the upper end of the closing valve housing 239 is provided with a cylinder 255 into which the extension 245 of the valve stem 243 extends. Operative within the cylinder 255 is a piston 257 normally urged to its lowermost position by a spring 259. The upper end of the extension 245 is provided with a stop such as a nut and washer arrangement 261 against which the interlock piston 257 may be moved. The lower end of the cylinder 255 communicates by means of a pipe 263 to the valve housing 209 of the opening valve and with the port 229 of that housing. Thus when the valve 213 of the opening valve mechanism 163 is open, compressed air may flow through the pipe 263 to the lower side of the interlock piston 257 so as to raise that piston against the stop 261. The effective fluid pressure area of the interlock piston 257 is made larger than the effective fluid pressure area of the piston 247 so that if the electromagnetically actuated pilot valve 249 is opened to admit compressed air to the top of the piston 247 tending to move the piston downwardly to open the valve 241, the force exerted upon the valve in a downward direction will be less than the force exerted by the interlock piston 257 in the upper direction. Consequently, the closing valve 241 will remain closed, and the opening valve 213 of the opening valve mechanism 163 will function in its normal manner to complete the opening operation. It will thus be seen that an opening impulse will always take preference over a closing impulse by reason of the interlocking arrangement between the opening and closing valves.

An auxiliary switch means 265 (Fig. 1) is mounted on the framework 11 adjacent the insulator 13. The auxiliary switch means 265 may be of any conventional construction embodying a plurality of sets of contacts forming a plurality of poles for control and indicating purposes. The operating lever of the auxiliary switch means 265 is connected by a linkage system 267, 269 and 271 to a rotatable member or crank arm 273 mounted on the lower cylinder head 133 of the disconnect contact operating cylinder 103. The rotatable member 273 is adapted to be partially rotated in opposite directions by the reciprocating movement of the disconnect operating piston 105, thereby operating the auxiliary switch means in accordance with the position of the movable disconnect contact member 39. The coupling means between the auxiliary switch means and the operating piston 105 is fully disclosed and claimed in the copending application of B. P. Baker and A. H. Bakken, Serial No. 431,395, filed February 18, 1942, and issued November 21, 1944, as Patent No. 75

2,363,283, to the assignee of the present invention.

Referring now to Fig. 7, which diagrammatically shows the circuits for electrically controlling the circuit interrupter, 275 and 277 designate a pair of supply conductors connected to a source of electrical energy (not shown). The winding of the solenoid 251 which controls the admission of compressed air to the operating cylinders for closing the contact members of the circuit interrupter is connected in an energized circuit 278 extending from the supply conductor 275 through the winding of the solenoid 251 and front contacts 281 of a closing relay 283 to the supply conductor 277. The energizing winding of the closing relay 283 is connected in an energizing circuit which extends from the supply conductor 277 through a conductor 288, back contacts 287 of a release relay 289, energizing winding of the closing relay 283, conductor 291, conductor 293 and through a manual closing control switch 295 and conductor 297 to the supply conductor 275. A reclosing relay 299 has contacts 301 connected in shunt to the closing control switch 295. The reclosing relay 299 may be energized to automatically reclose the circuit interrupter in a manner well known in the art.

The energizing winding of the release relay 289 is connected in an energizing circuit which extends from the supply conductor 277 through a conductor 303, through an auxiliary switch 305 which is adapted to be closed when the disconnect contact member 39 of the circuit interrupter reaches closed position, through a conductor 307, energizing winding of the release relay 289, conductor 309, through front contacts 311 of the closing relay 283 and through a conductor 313 to the supply conductor 275.

A stick circuit is provided for maintaining the closing relay 283 energized after a momentary operation of the manual closing control switch 295 or the contacts 301 of the reclosing relay. This stick circuit extends from the supply conductor 277 through the conductor 288, back contacts 287 of the relay 283, conductor 315, energizing winding of the closing relay 283, conductor 291 and front contacts 311 of the closing relay and through conductor 313 to the supply conductor 275.

A locking circuit is also provided for maintaining the release relay 289 energized after the disconnect contacts of the interrupter close and until the manual closing control switch 295 has been opened. This locking circuit for the release relay 289 extends from the supply conductor 277 through conductor 285, front contacts 317 of release relay 289, through the winding of the release relay 289, conductor 293, manual closing control switch 295 and conductor 297 to the supply conductor 275. The purpose of this locking circuit is to prevent pumping of the circuit interrupter in the event that the circuit interrupter fails to remain closed and the manual closing control switch 295 is held by the operator in closed position.

The winding of the solenoid 227 for controlling the opening valve 163 which controls the flow of compressed air to the cylinder 99 for effecting opening operation of the circuit interrupter, and the winding of the solenoid 93 which controls opening of the blast valve 71 are connected in parallel in an energizing circuit which extends from the supply conductor 275 through a conductor 321, front contacts 323 of an opening relay 325, conductor 327, the energizing wind-

ings of the solenoids 227 and 93 in parallel, conductor 329, through auxiliary contacts 331 which are open when the disconnect contact member 39 is in open position, and through conductor 303 to the supply conductor 271. The branch or portion of the circuit including the winding of the solenoid 93 has a pair of auxiliary contacts 330 connected in series with the winding of solenoid 93, and these auxiliary contacts open as soon as the disconnect contact member 39 starts its opening movement, thereby deenergizing the solenoid 93 so that the blast valve returns to closed position.

The energizing winding of the opening relay 325 is connected in an energizing circuit which extends from the supply conductor 275 through conductor 297, through the contacts 333 of a protective relay 335 through conductor 337, energizing winding of opening relay 325, conductor 339 through auxiliary contacts 341 which are closed when the disconnect contact member 39 is in closed position and which are opened when the disconnect contact member reaches full open position, and through conductor 303 to the supply conductor 271.

A manual opening control switch 343 is connected in shunt to the contacts 333 of the protective relay for the purpose of manually controlling opening of the circuit interrupter by energizing the opening relay over the circuit previously described.

A stick circuit is provided for maintaining the opening relay 325 energized after a momentary closing of the contacts 333 or 343 and until the disconnect contact member 39 reaches full open position. This stick circuit extends from the conductor 275 through a portion of conductor 321, front contacts 345 of the opening relay 325, energizing winding of the opening relay 325, conductor 339, auxiliary contacts 341, and conductor 303 to the supply conductor 271.

A circuit interrupter is adapted to be quickly automatically reclosed immediately following opening of the disconnect contact member 39 through the agency of the reclosing relay 299 providing the circuit of the reclosing relay is rendered operative by a manual control switch 351. If quick automatic reclosing is not desired, the manual switch 351 may be opened thus rendering reclosing relay 299 inoperative.

The protective relay 335 may be of the current overload type which is operative in response to an overload in the main circuit 353 controlled by the circuit interrupter. The operating coil of the protective relay 335 is adapted to be energized through the agency of a current transformer 355 associated with the main circuit conductor 353.

The operation of the circuit interrupter is as follows: Assuming the circuit interrupter to be in closed position as shown in Fig. 7, when a predetermined overload or short circuit occurs in the main circuit 353 controlled by the interrupter, the protective relay 335 is immediately energized and closes its contacts 333 to effect energization of the opening relay 325. The operation of the opening relay 325 completes the energizing circuit for the solenoid 227 of the opening valve mechanism 163 and for the solenoid 93 of the blast valve mechanism 71. Compressed air from the tank 67 then flows through the opening valve 163, through passages previously described, into the upper end of the operating cylinder 99 to effect downward movement of the piston 101 thereby operating the movable arcing

contact member 31 to open position. At the same time, the flow of compressed air to the upper end of the operating cylinder 99 opens the dump valve 187 thereby connecting the lower ends of the operating cylinders 99 and 103 to atmosphere. As soon as the arcing contact operating piston 101 has moved a predetermined distance in an opening direction, it uncovers a port connected to the pipe 173 to admit compressed air to the upper end of the disconnect operating cylinder 103 through the pipe 173. By the time the contact member 31 reaches full open position, the flow of compressed air into the operating cylinder 103 starts to move the piston 105 downwardly to open position, thereby effecting movement of the disconnect contact member 39 to open position thereby completing the opening operation of the circuit interrupter. As soon as the disconnect contact member 39 starts its opening movement the auxiliary contacts 330 open and deenergize the blast valve solenoid 93 thereby causing the blast valve 71 to close.

As soon as the disconnect contact member 39 reaches full open position, the auxiliary contacts 341 open and effect deenergization of the opening relay 325 thereby effecting closing of the opening valve 163 by deenergizing the solenoid 227 which controls this valve.

During the opening operation of the arcing contact member 31, a blast of compressed air is directed to the arcing contacts in interrupting element 23 to quickly extinguish the arc drawn by these contacts. This blast valve returns to closed position, however, as soon as the disconnect contact member 39 starts to open.

The circuit interrupter is adapted to be quickly automatically reclosed immediately following an opening operation thereof through the agency of the reclosing relay 299, energization of which may be effected by auxiliary contacts (not shown) operated when the disconnect contact member 39 reaches open position. Closing of the reclosing relay contacts 301 completes an energizing circuit for the closing relay 283. When the closing relay 283 is energized, it completes its previously described circuit for energizing the winding 251 of the closing valve mechanism 165 thereby opening the closing valve and admitting compressed air to the lower end of the operating cylinder 99. The flow of compressed air to the lower end of the operating cylinder immediately effects opening of the dump valve 187 which opens the upper ends of the cylinders 99 and 103 to atmosphere. The compressed air admitted to the lower side of the piston 101 moves this piston upwardly to effect movement of the arcing contact member 31 to closed position. After the operating piston 101 is moved upwardly a predetermined distance, it uncovers the port which is connected by the pipe 183 to the lower end of the cylinder 103, thereby admitting compressed air to the lower end of the disconnect contact operating cylinder 103. After the arcing contact member 31 has reached closed position, the compressed air admitted to the lower side of the operating piston 105 effects movement of the piston upwardly thereby moving the disconnect contact member 39 to closed position. As soon as the disconnect contact member 39 reaches closed position, the auxiliary contacts 305 close and effect energization of the release relay 289. Energization of the release relay 289 effects deenergization of the closing relay 283 by opening of the contacts 287. The release relay 289 is then deenergized by the opening of the contacts 311 of the closing relay. When the closing

relay 283 drops out, the solenoid 251 is deenergized and the closing valve 165 returns to closed position.

If the fault condition which caused opening of the breaker has cleared by the time the disconnect contact member reaches closed position, the circuit interrupter will remain closed. However, if the fault condition is still present upon closing of the disconnect contacts, the protective relay 335 will again be energized and immediately effect opening operation in the manner previously described. A lockout device may be provided in the automatic reclosing circuit to limit the number of automatic reclosing operations to one or any other desired number in a manner well known in the art.

Since the main conductor circuit may be completed slightly before the disconnect contact member reaches the fully closed position, fault-responsive relay 335 may be energized prior to complete closing of the interrupter if a fault condition is present in the main circuit. Under such conditions, the opening relay effects opening of the valve mechanism 163 and this will result in quick reversal of the switching operation from closing to opening due to the fact that the opening and closing valves are interlocked in the manner previously described, whereby an opening impulse will always take precedence over a closing impulse.

The pneumatic interlocking arrangement of the two operating cylinders insures the proper sequence of operation of the contact members 31 and 39 irrespective of the speed of operation of the operating means, and the dump valve arrangement previously described provides for high speed opening and reclosing operations of the interrupter.

In accordance with a modification of the invention, the arcing contact member 31 may be automatically returned to closed position immediately after the supply of opening air is cut off, in order to remove potential across these contacts. For this purpose a spring 361 may be provided as indicated in Fig. 8 for biasing the movable arcing contact member 31 to closed position. The spring does not otherwise affect the operation of the system which is the same as that previously described. The flow of compressed air to the lower end of the operating cylinder 99 in this instance insures that the arcing contact member 31 will be moved to the fully closed position before the disconnect contacts are closed.

While the invention has been disclosed in accordance with the provisions of the patent statutes, it is to be understood that various changes in the structure, details and arrangement of parts thereof may be made without departing from some of the essential features of the invention. It is desired, therefore, that the language of the appended claims be given the broadest reasonable interpretation permissible in the light of the prior art.

We claim as our invention:

1. A circuit interrupter comprising a pair of current interrupting contacts, a pair of disconnect contacts connected in series therewith, compressed gas operating means for opening said pairs of contacts in a predetermined sequence and for closing said pairs of contacts in a predetermined sequence, said operating means comprising a double acting compressed gas motor for opening and closing said current interrupting contacts, a separate double acting compressed gas motor for opening and closing said disconnect contacts, a

source of compressed gas for operating said motors, control valve means for controlling the flow of compressed gas to the motor of said current interrupting contacts to effect opening or closing of the circuit interrupter, and means pneumatically interlocking said motors to cause said disconnect contacts to be opened only after said current interrupting contacts have opened a predetermined distance during opening operation of the circuit interrupter and for causing said disconnect contacts to close after said current interrupting contacts are completely closed during closing operation of the interrupter, said interlocking means comprising gas connections for admitting compressed gas to said disconnect contact motor arranged to be opened and closed by said current interrupting contact motor.

2. A circuit interrupter comprising a pair of current interrupting contacts, a pair of disconnect contacts connected in series therewith, compressed air operating means for opening said pairs of contacts in a predetermined sequence and for closing said contacts in a predetermined sequence, said operating means comprising a separate double acting compressed air motor for each pair of contacts for opening and closing the same, a source of compressed air for actuating said motors, control valve means for controlling the flow of compressed air to said motors for effecting opening and closing of the circuit interrupter, and means pneumatically interlocking said motors for causing said disconnect contacts to open only after said current interrupting contacts have opened a predetermined distance during opening operation of the circuit interrupter and for causing said pairs of contacts to be closed in a predetermined sequence during a closing operation of the interrupter, said pneumatic interlocking means comprising air passages connecting said motors and controlled by said current interrupting contact motor to admit compressed air to said disconnect contact motor.

3. A circuit interrupter comprising a pair of current interrupting contacts, a pair of disconnecting contacts connected in series therewith, compressed gas operating means for opening and closing said contacts, said operating means including a separate cylinder and piston for each pair of contacts, a source of compressed gas for operating said contacts, opening valve means for controlling the flow of compressed gas to one end of the operating cylinder for said interrupting contacts for opening the contacts, closing valve means for controlling the flow of compressed gas to the other end of the operating cylinder of said interrupting contacts for closing the contacts, and means comprising gas passages connecting the ends of the operating cylinder of said disconnecting contacts to predetermined points of said interrupting contact operating cylinder for pneumatically interlocking said contacts to cause said disconnecting contacts to open after said interrupting contacts have opened a predetermined distance during opening operation of the interrupter and to cause said disconnecting contacts to close after said interrupting contacts have closed during closing operation of the interrupter.

4. A circuit interrupter comprising a pair of current interrupting contacts, a pair of disconnect contacts connected in series therewith, compressed air operating means for opening said pairs of contacts in a predetermined sequence and for closing said pairs of contacts in a predetermined sequence, said operating means including a cylinder and double acting piston therein for open-

ing and closing said current interrupting contacts, another cylinder and double acting piston therein for opening and closing said disconnect contacts, a source of compressed air for operating said pistons, opening valve means for controlling the flow of compressed air to one end of the current interrupting contact operating cylinder to effect opening operation of the circuit interrupter, means separate from said opening valve means 5 operable to cause a blast of compressed air to extinguish the arc drawn between said current interrupting contacts during opening of said contacts, closing valve means for controlling the flow of compressed air to the opposite end of said current interrupting contact operating cylinder to effect closing operation of the circuit interrupter, and means including a pair of air passages connecting the ends of said disconnect contact operating cylinder to predetermined points of said current interrupting contact operating cylinder for pneumatically interlocking said pistons to cause said disconnect contacts to be opened only after said current interrupting contacts have opened a predetermined distance during opening operations of the circuit interrupter and to cause said 10 disconnect contacts to close after said circuit interrupting contacts during closing operation of the interrupter.

5. A circuit interrupter comprising a pair of current interrupting contacts, a pair of disconnect contacts connected in series therewith, compressed air operating means for opening said pairs of contacts in a predetermined sequence and for closing said pairs of contacts, said operating means including a cylinder and double acting piston therein for opening and closing said current interrupting contacts, another cylinder and double acting piston therein for opening and closing said disconnect contacts, a source of compressed air for operating said pistons, opening valve means for controlling the flow of compressed air to the opening end of said current interrupting contact operating cylinder to effect opening operation of the circuit interrupter, closing valve means for controlling the flow of compressed air to the closing end of said cylinders to effect a closing operation of the circuit interrupter, means including an air passage connecting the opening end of the disconnect contact operating cylinder to a predetermined point of the current interrupting contact operating cylinder for causing said disconnect contacts to be opened only after said current interrupting contacts have opened a predetermined distance during opening operations of the circuit interrupter, and a single dump valve means operated by the flow of compressed air to the opening end of said current interrupting contact operating cylinder for dumping air from the closing ends of both of said cylinders directly to atmosphere.

6. A circuit interrupter comprising a pair of current interrupting contacts, a pair of disconnecting contacts connected in series therewith, compressed air operating means for opening said pairs of contacts in a predetermined sequence and for closing said pairs of contacts, said operating means comprising a cylinder and double acting piston therein for opening and closing said current interrupting contacts, another cylinder and double acting piston therein for opening and closing said disconnect contacts, a source of compressed air for operating said pistons, opening valve means for controlling the flow of compressed air to the opening end of said current interrupting contact operating cylinder to effect

5 circuit opening operation of the circuit interrupter, closing valve means for controlling the flow of compressed air to the closing end of said current interrupting contact operating cylinder to effect closing operation of the circuit interrupter, means including a pair of air lines connecting the ends of said disconnect contact operating cylinder to predetermined points of said current interrupting contact operating cylinder for causing said disconnect contacts to be opened only after said current interrupting contacts have opened a predetermined distance during an opening operation and for causing said disconnect contacts to close after said current interrupting contacts during a closing operation, dump valve means operated by the flow of compressed air to the opening end of said current interrupting contact operating cylinder for simultaneously dumping air from the closing ends of said cylinders to atmosphere, and a single dump valve means operated by the flow of compressed air to the closing end of said current interrupting contact operating cylinder for simultaneously dumping air from the opening ends of both of said cylinders to atmosphere.

7. A circuit interrupter comprising a pair of current interrupting contacts, a pair of disconnecting contacts connected in series therewith, compressed air operating means for opening said pairs of contacts in a predetermined sequence and for closing said pairs of contacts, said operating means comprising a cylinder and double acting piston therein for opening and closing said current interrupting contacts, another cylinder and double acting piston therein for opening and closing said disconnect contacts, a source of compressed air for operating said pistons, opening valve means for controlling the flow of compressed air to the opening end of said current interrupting contact operating cylinder to effect opening operation of the circuit interrupter, closing valve means for controlling the flow of compressed air to the closing ends of said cylinders to effect closing operation of the circuit interrupter, means including an air passage connecting the end of said disconnect contact operating cylinder to a predetermined point of said current interrupting contact operating cylinder for causing said disconnect contacts to be opened only after said current interrupting contacts have opened a predetermined distance during opening operation of the circuit interrupter, and a single dump valve means operated by the flow of closing compressed air for causing the dumping 55 of air from the opening ends of both of said cylinders to atmosphere.

8. A circuit interrupter comprising a pair of current interrupting contacts, a pair of disconnecting contacts connected in series therewith, compressed air operating means for opening said pairs of contacts in a predetermined sequence and for closing said pairs of contacts, said operating means comprising a cylinder and double acting piston therein for opening and closing said current interrupting contacts, another cylinder and double acting piston therein for opening and closing said disconnect contacts, a source of compressed air for operating said pistons, opening valve means for controlling the flow of compressed air to the opening end of said current interrupting contact operating cylinder to effect opening operation of the circuit interrupter, closing valve means for controlling the flow of compressed air to the closing ends of said cylinders to effect closing operation of the circuit in-

terrupter, means including an air passage connecting the end of said disconnect contact operating cylinder to a predetermined point of said current interrupting contact operating cylinder for causing said disconnect contacts to be opened only after said current interrupting contacts have opened a predetermined distance during opening operation of the circuit interrupter, and a single dump valve means operated by the flow of closing compressed air for causing the dumping of air from the opening ends of both said cylinders to atmosphere, and a single dump valve means operated by the flow of compressed air to the opening end of said circuit interrupting contact operating cylinder for dumping air from the closing ends of both of said cylinders to atmosphere.

9. A circuit interrupter comprising a pair of current interrupting contacts, a pair of disconnect contacts connected in series therewith, compressed air operating means for opening and closing said pairs of contacts, said operating means comprising a cylinder and piston therein for operating said current interrupting contacts, another cylinder and double acting piston therein for opening and closing said disconnect contacts, a source of compressed air for operating said pistons, opening valve means for controlling the flow of compressed air to one end of said current interrupting contact operating cylinder to effect opening operation of the circuit interrupter, closing valve means for controlling the flow of compressed air to one of said cylinders for effecting closing operation of the circuit interrupter, means including an air passage connecting the opening end of said disconnect contact operating cylinder to a predetermined point of said current interrupting contact operating cylinder for causing said disconnect contacts to be opened only after said current interrupting contacts have opened a predetermined distance during opening operation of the circuit interrupter, and spring means operable to effect reclosing of said current interrupting contacts after the flow of compressed air for opening the circuit interrupter is shut off.

10. A circuit interrupter comprising a pair of arcing contacts separable to provide a current interrupting break, a pair of disconnect contacts connected in series therewith and at least one of which is movable to provide an isolating break, compressed gas operating means for opening and closing said contacts including a cylinder and double acting piston therein for opening and closing said current interrupting contacts, another cylinder and double acting piston therein for opening and closing said disconnect contacts, a source of compressed gas for operating said pistons, opening valve means for controlling the flow of compressed gas to one end of said arcing

- contact operating cylinder to effect opening operation of the circuit interrupter, closing valve means for controlling the flow of compressed gas to the opposite end of said arcing contact operating cylinder to effect closing operation of the circuit interrupter, means including a pair of gas passages connecting the ends of said disconnect contact operating cylinder to predetermined points of said arcing contact operating cylinder for causing said disconnect contacts to be opened only after said arcing contacts have opened a predetermined distance during opening operation of the circuit interrupter, and for causing closing of said pairs of contacts in a predetermined sequence during closing operation of the circuit interrupter, and spring means operable to reclose said arcing contacts after the compressed air for opening the circuit interrupter is shut off.
11. A circuit interrupter comprising a base, supporting insulator means mounted on said base, an arc extinguishing device carried by said insulator means, said arc extinguishing device having a pair of separable arcing contacts for establishing a current interrupting break, a pair of disconnect contacts connected in series with said arcing contacts, one of said disconnect contacts being movable to establish an isolating break, and being electrically connected to one of said arcing contacts, compressed air operating means for opening said pairs of contacts in a predetermined sequence, and for closing said pairs of contacts, said operating means comprising a cylinder and double acting piston therein for opening and closing said arcing contacts, another cylinder and double acting piston therein for opening and closing said disconnect contacts, a source of compressed air for operating said pistons, said pistons and cylinders being disposed at line potential and supported by said insulator means, opening valve means for controlling the flow of compressed air to one end of the arcing contact operating cylinder to effect opening operation of the circuit interrupter, closing valve means for controlling the flow of compressed air to an end of one of said cylinders to effect closing operation of the circuit interrupter, and means including a pair of air passages connecting predetermined points of said cylinders together for causing said disconnect contacts to be opened only after said arcing contacts have opened a predetermined distance during opening operation of the circuit interrupter and for causing said pairs of contacts to close in a predetermined sequence.
